United States Patent Office.

ARMAND MANUEL, OF REIMS, FRANCE.

Letters Patent No. 61,624, dated January 29, 1867.

IMPROVED DEVICE FOR UNCORKING BOTTLES.

The Schedule referred to in these Letters Patent and making part of the same.

TO WHOM IT MAY CONCERN:

Be it known that I, ARMAND MANUEL, of Reims, in the empire of France, have invented a certain new and improved Method of Uncorking Bottles; and I hereby declare the following to be a full, clear, and exact description of the same, reference being had to the accompanying drawings.

The object of my invention is to provide a ready means for uncorking bottles containing gaseous and foaming or sparkling liquids, and especially champagne wines.

The method I employ consists essentially in breaking or loosening the wire, or other band which retains the cork, by means of a device attached to the neck of the bottle, and forming part of the pieces by which the cork is kept in place. This device or instrument is held upon the wire which passes around the neck of the bottle, and, by taking hold of it and turning it in any direction longitudinally or transversely, the wire is twisted and broken. It is in effect a lever, having its fulcrum or point of support on the bottle, and actuated by the hand to overcome the resistance offered by the wire; and by means of this detaching lever I am enabled to dispense with the use of tweezers or a knife, which may not always be conveniently at hand, and to provide each bottle with the means by which the wire or band for holding the cork down can be readily loosened and removed.

The nature of my invention will be fully comprehended by reference to the accompanying drawings, in which I have shown my apparatus applied in various manners and under different forms to bottles containing gaseous liquids.

Figure 1 represents a simple wire clasp or band, *a*, carrying the detaching lever *x*, which here has the form of a sinuous or serpentine tongue. Its upper end is bent over so as to form a loop or slide, through which is inserted the wire which encircles the neck of the bottle, and holds the clasp *a* down upon the cork.

In Figure 2 the detaching lever is attached to a double clasp, composed of two bands, *a b*, shown separately in Figures 3 and 4. The band or tie *a* is composed of a piece of wire doubled and twisted so as to form a loop or eye at one end, the loose ends *e* and *f* being untwisted and of such length that after the clasp is fitted over the cork they can encircle the neck of the bottle. The tie *b* is long enough to pass over the cork and to come below the flange on the neck of the bottle, and is made of wire doubled by turning the two ends towards each other so that they will meet in the centre of the band or tie. The two parts are then twisted in opposite directions so as to form eyelets or rings *c d* in each end of the tie. The tie *b* is placed transversely or crosswise to and under the tie *a*, and the two ends *e* and *f* of the latter are inserted through the eyes *c d*. The detaching lever is suspended by the loop or slide *z y*, through which is passed one of the ends, *e f*. The double clasp is placed on the cork, as shown in fig. 2, after which the two ends *e f* are drawn around the neck of the bottle and twisted together.

Figure 5 represents the same clasp placed over a cap or head-piece of tin or other metal previously spread over the top of the cork.

Figure 6 represents the detaching lever and its clasp applied to a cork held in place by an ordinary tie of twine or cord.

The method of removing the clasp from the cork will be readily understood by reference to Figure 7. It is only necessary to turn or draw the lever to the right or left tangentially to the bottle, and the wire lifted on one side by the part *y* of the slide and pressed down on the sides by the part *z*, will be almost immediately broken. When this is done the clasp is removed without trouble, and the cork, being no longer restrained, yields to the expansive action of the gas and is driven from the bottle. The lever may be made of any metal and of any desired dimensions or form.

A particular arrangement of the lever is shown in Figure 8 applied to an ordinary clasp. It has the form of a heart pierced by a hole, *o*, for the passage of the wire which is drawn around the neck of the bottle. By taking this piece between the thumb and forefinger, and turning it as if it were a key, the wire will be at once broken.

Having described my invention, what I claim, and desire to secure by Letters Patent, is—

1. The method of removing or breaking the wire or other clasp or tie which holds the cork in the bottle by means of a detaching lever or equivalent device attached to and secured upon the said clasp or tie, substantially as set forth.
2. The combination, with one or more clasps or ties applied to the cork, as described, of a detaching lever or similar device under the arrangement and for operation substantially as shown and specified.

In testimony whereof I have signed my name to this specification before two subscribing witnesses,

A. MANUEL.
